HANGER AND HAMMER ASSEMBLY FOR
HAMMER MILLS

George Alexander Millerd, New London, Wis.

Application December 17, 1948, Serial No. 65,877

5 Claims. (Cl. 241—197)

1

This invention relates to hammer mills and more particularly to a novel mode of assembling the hangers and hammers.

It is an object of my invention to provide a simple and rugged structure whereby hammers may be easily and rapidly joined to their respective hangers.

It is another object of my invention to provide a hanger and hammer assembly suitable for incorporation in any type of hammer mill.

It is a further object of my invention to provide a structure which may be used either as an end crushing hammer or a side crushing hammer.

It is a further object of my invention to provide a hanger and hammer assembly wherein the hammer may be reversed.

In general my invention contemplates, hangers having a novel shape comprising protuberances for engaging correspondingly-shaped channels in the hammer with which they are associated. The particularly novel feature resides in having the hangers enter the hammer at the side thereof, although the invention is adaptable for entrance at the ends of the hammer also.

My invention will now be described in conjunction with the appended drawing, in which,

Figure 1 is a section through a portion of a mill showing a side view of one of my hangers and the respective hammer;

Figure 2 is a section through 2—2 of Figure 1;

Figure 3 is a front view of another form, shown looking toward a side of the hammer;

Figure 4 is a section through 4—4 of Figure 3;

Figure 5 is a section through 5—5 of Figure 3;

Figure 6 shows a view of another modification of my invention;

Figure 7 is a horizontal section taken through Figure 6;

Figure 8 is a section through 8—8 of Figure 6;

Figure 9 is an end elevational view of the hammer illustrated in Figures 3 to 5, inclusive; and

Figure 10 is a similar end elevational view of the hammer illustrated in Figures 6 to 8.

With reference to Figures 1 and 2, my invention comprises L-shaped hangers 10 arranged to engage in the ends of a hammer 14, and including substantially vertical arms 21 and substantially horizontal arms 20'. Hangers 10 are pivotally suspended in the usual manner from discs 17 of a hammer mill. At the outer end of each hanger arm 20' an elongated transverse head 20 is formed of the material thereof in a direction generally parallel to the main arm 21. These heads 20 are inserted in correspondingly shaped openings or slots 23 in the hammer ends, as will be understood from consideration of the drawing.

2

It will be apparent from the above description that the hammer 14 is suspended at its ends by means of the hangers 10 in a simple but very rugged manner, it being noted that each hanger 10 has a toe extension 22 extended beyond the head 20 to the outer side of the respective hammer 14. Thus considerable bearing area is provided for suspension of the hammer at each end thereof. The arms 20' and toe extensions 22 engage in transverse slots 23', formed in the opposite ends of the hammer 14 and extending at right angles to and intersecting the openings 23, as shown.

The particular shape of the head 20, as shown in Figures 1 and 2, may be varied as a matter of design; e. g. they could be circular, diamond-shaped, square or rectangular, etc. and need not necessarily be symmetrical with respect to the axis of toe 22.

20 The discs 17 are keyed at 45 to a drive shaft 46, and each pair of hangers 10 is pivotally mounted upon a pin 47 extending through openings 48 in the discs. Upon each pin 47 is mounted a spacer sleeve 49 of such length as to engage the side faces of the two inside discs 17. A cotter pin 50 is inserted through openings in the sleeve 49 and the pin 47 to restrain the pin from relative displacement with respect to the discs 17.

25 Removal of the cotter pin 50 permits the pin 47 to be detached from the discs 17, thereby providing an arrangement wherein the hangers 10 may be easily connected with or detached from the discs 17. Since the hangers 10 are each located between two discs 17, the hangers are restrained from relative movement longitudinally 30 of their associated pins 47. Thus the hammer 14 is effectively connected with its associated hangers 10 so that the hammer is restrained from relative movement with respect to the hangers, but with the construction such as to facilitate 35 detachment of the hammer from the hangers through disconnection of the hangers from the discs.

While the form just described is suitable for 40 suspending hammers at their ends, it will be appreciated that the nature of my invention is such as to make it readily adaptable for suspending hammers by engaging them at their sides. There are certain advantages to be gained thereby, 45 namely, the fact that a narrower hammer can be used, narrow hammers being self-sharpening with use. Further, side suspension results in a generally stronger structure than end suspension. Thus in the form of my invention, as shown in 50 Figures 3, 4 and 5, I provide a longitudinal slot 55

23 substantially centrally of a hammer 24 and of sufficient length as to accommodate the vertical height of the heads 20. Accordingly, the hangers and hammers are readily assembled by thrusting the heads 20 into slot 23, substantially centrally thereof, and then sliding the hangers toward the opposite ends of the hammer 24, wherein the heads engage in elongated end openings or channels 27 for locking engagement. I prefer to contour the openings 27 to match the 10 contours of the heads 20, although matching is not absolutely essential. The slot 23 has end reduced extensions 23', extending at right angles to and intersecting the elongated openings 27. The openings 27 may extend through the opposite ends of the hammer 24, as shown at 30. The slot extensions 23' receive the arms 20' and toe extensions 22 therein, when the heads 20 engage in the inner ends of the elongated openings 27, Figures 4 and 5.

It will be appreciated that channels 27 are suitably spaced so as to provide balanced suspension points for the respective hammer. Although the ends of the hammer may be left open as indicated at 30, it will be appreciated the hanger-hammer assembly joints are protected from abrasive or percussion action due to contact with materials in the mill.

In another form of my invention, as shown in Figures 6, 7 and 8, hanger entrance into the side of the hammer is likewise utilized. This modification, however, is provided with a hammer 33 having a longitudinal slot 35 and elongated end openings or channels 37 extending from the ends thereof into slot 35. Hangers 40 are provided with laterally extending heads 43 for engagement with channels 37, and it will be appreciated that the same shape in transverse cross-section of the heads may be used as disclosed in Figure 1, if desired, it being noted, however, that such heads do not extend vertically above or below the toe of the hanger but are in effect lateral toe extensions formed at right angles thereto. This particular construction is exceedingly rugged and it will be noted that the main body portion of the hangers, being spaced inwardly from the ends of the hammer, is protected from abrasive and percussion action in the mill.

The constructions which I have shown are all suitable for providing reversal of their respective hammers, as desired. Further, owing to the novel mode of assemblage disclosed hereinabove, the hangers and hammers may be so rapidly assembled or dissembled that it would be entirely feasible to provide sets of hammers of varying length so that progressively shorter hangers could be substituted for each other as the material of the hammers is worn away with use.

While I have shown certain modes of carrying out my invention, it will be appreciated that many modifications may be made without departing from the spirit thereof, and, accordingly, I do not seek to be limited by the specific disclosure, except as set forth in the appended claims.

What I claim:

1. In a hammer mill, a hammer bar provided in its opposite ends with transverse slots which extend through the opposite sides of the hammer bar, the opposite ends of the hammer bar also having elongated openings extending substantially at right angles to the slots and crossing the slots and extending beyond the opposite sides of the slots, the openings and slots being of substan-

tially the same depth and having their bottoms terminating longitudinally inwardly of the opposite ends of the hammer bar, and a pair of L-shaped hangers disposed adjacent to the opposite ends of the hammer bar and supporting the hammer bar and including arms which extend transversely of the hammer bar and engage within the slots at the opposite ends of the hammer bar, the arms including transverse elongated heads which extend substantially at right angles to the arms and slots and engage within the elongated openings crossing the slots, the arms and heads being substantially of the same width and of a width substantially equal to the depth of the slots and openings so that the arms and heads are disposed substantially flush with the opposite ends of the hammer bar.

2. In a hammer mill, an elongated hammer bar provided near its longitudinal center with an elongated longitudinally extending slot, the slot extending transversely through opposite sides of the hammer bar, the hammer bar being provided at the opposite ends of the slot with relatively narrow slot extensions leading into the opposite ends of the slot and disposed laterally inwardly of the opposite sides of the slot and extending through the opposite sides of the hammer bar, the hammer bar being provided in its opposite ends with transversely elongated longitudinal openings extending through the opposite ends of the slot and intersecting and crossing the relatively narrow slot extensions, and hangers supporting the hammer bar and including arms provided at their free ends with transverse elongated heads projecting upon opposite sides of the arms, the arms and heads being insertable into the slot of the hammer bar and shiftable toward the opposite ends of the slot so that the arms engage within the relatively narrow slot extensions and the elongated heads engage within the inner ends of the transversely elongated longitudinal openings.

3. In a hammer mill, an elongated hammer bar provided between its ends and near its longitudinal center with a wide transverse slot extending therethrough, the hammer bar being provided adjacent to the opposite ends of the slot with relatively narrow transverse slot extensions leading into the opposite ends of the slots and extending through opposite sides of the hammer bar, the sides of the slot extensions being disposed laterally inwardly of the sides of the slot, the hammer bar being provided in its opposite ends with longitudinal openings which lead into the opposite ends of the slot and which are substantially in longitudinal alignment, the longitudinal openings being transversely elongated in a direction substantially at right angles to the narrow slot extensions, the longitudinal openings intersecting the slot extensions and extending transversely beyond the opposite sides of the slot extensions, the opposite sides of the transversely elongated longitudinal openings being substantially flush with the opposite sides of the slot, and a pair of L-shaped hangers supporting the hammer bar and including elongated substantially straight arms provided at their free ends with transverse elongated heads which project laterally outwardly upon opposite sides of the arms, the lengths of the heads being substantially equal to the width of the slot, the widths of the arms being substantially equal to the widths of the slot extensions, the arms and heads being insertable into the slot and shiftable toward the opposite ends of the slot so that the arms engage

within the slot extensions while the heads engage within the transversely elongated longitudinal openings, whereby the inner sides of the arms and heads are substantially flush with the opposite ends of the slot.

4. In a hammer mill, an elongated hammer bar provided near its longitudinal center with an elongated slot which extends longitudinally of the hammer bar and transversely entirely through the same, the hammer bar being provided in its opposite ends with aligned longitudinal openings leading into the opposite ends of the slot and being transversely elongated in a direction substantially at right angles to the sides of the slot, and a pair of hangers supporting the hammer bar and including arms provided at their ends with transverse heads, the arms and heads being insertable into the slot and shiftable toward the opposite ends of the slot so that the heads may engage within the longitudinal openings for detachably locking the hammer bar to the hangers.

5. In a hammer mill, an elongated hammer bar provided near its longitudinal center with an elongated longitudinally extending slot, the slot extending transversely of the hammer bar and through opposite sides of the same, the hammer bar being provided in its opposite ends with aligned longitudinal openings which are transversely elongated in a direction substantially at right angles to the opposite sides of the slot, and a pair of hangers supporting the

hammer bar and including arms provided at their free ends with transverse heads which project laterally beyond the outer sides of the arms, said heads being transversely elongated in a direction substantially at right angles to the arms and being of substantially the same shape in transverse cross-section as the longitudinal openings of the hammer bar, the arms and heads being insertable into the slot of the hammer bar and shiftable longitudinally toward the opposite ends of the slot so that the heads may engage within the longitudinal openings for detachably securing the hammer bar to the hangers.
